UNITED STATES PATENT OFFICE

2,247,844

REAR DOOR LOCK FOR VEHICLES

John A. Lamb, Detroit, Mich.

Application May 16, 1940, Serial No. 335,636

1 Claim. (Cl. 292—182)

This invention relates to motor vehicle door locks, and its general object is to provide locks for the rear doors of a four door vehicle of the sedan type, that are automatically operated solely by and upon opening and closing the front doors, and so that the rear doors are held securely locked when the front doors are in closed position and cannot be manually opened until the front doors are moved to open position, therefore it will be seen that by the use of my locks, a four door vehicle has all of the safety features of a two door vehicle of the coach type, as for example the locks prevent the possibility of the occupants of the rear seat from opening the rear doors while the vehicle is in motion, and they also eliminate the possibility of forgetting to lock the rear doors when leaving the vehicle.

A further object is to provide a lock for a four door vehicle that can be applied to vehicles now in use, without making any changes thereto, and merely by securing the lock parts to the inner faces of the doors and the center posts or pillars, but when applied on new vehicles, it is preferred that the parts be concealed by installing them within the center posts and doors.

Another object is to provide a lock of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a horizontal sectional view taken through the center post and doors of a vehicle, with one form of my lock installed thereon, and with the lock parts in locked position.

Figure 2 is a sectional view taken approximately on line 2—2 of Figure 1, looking in the direction of the arrows.

Figure 3 is a view similar to Figure 2, with the parts in unlocked position.

Figure 4 is a detail perspective view of the front door actuated member for operating the rear door bolt.

Figure 5 is a similar view of the rear door bolt.

Figure 6 is a horizontal sectional view similar to Figure 1, but illustrates the modified or concealed form of my lock.

Referring to the drawing in detail, and particularly to Figures 1 to 5 inclusive, the letter A indicates a center post or pillar of a four door vehicle, B the rear door and C the front door, all of which are of the usual construction and require no change to the structure thereof when applying this form of my lock thereto.

This form of lock includes a relatively narrow rectangular casing 1 of a length co-extensive with the width of the post A and is fixed to the inner face of the post by screws 2 or the like, for disposal of the ends of the casing flush with the sides of the post, as clearly shown in Figure 1. The casing includes top and bottom walls 3 and 4, an outer side wall 5, a removable inner side wall 6, and a rear end wall 7, while the front end of the casing is open.

Mounted for slidable movement within the casing 1 is a front door actuating member that includes an elongated cam block 8 having a beveled outer face and formed on and extending from the flat inner face thereof is a pair of parallel T-shaped stems 9 between which is slidably mounted the head 10 of a T-shaped stem 11 of a latch bolt 12 for the rear door, the latch bolt 12 being mounted in and movable through an opening in the rear end wall 7, while the cam block is movable through the open front end of the casing, as clearly shown in Figures 2 and 3.

The head 10 is urged and normally held engaged with the heads 13 of the T-shaped stems 9, by an expansion coil spring 14 disposed between the head 10 and the cam block 8.

Formed on or otherwise secured to the inner surface of the top and bottom walls for disposal in alignment with each other, is a pair of lugs 15 providing fixed abutment means for one of the ends of a pair of expansion coil springs 16 that have their opposite ends engaged with the inner face of the cam block, and the ends of the springs 14 and 16 are mounted on studs 17 formed on the cam block 8, the head 10 and the lugs 15, to hold the springs properly positioned with respect to their bearing parts, as clearly shown in Figures 2 and 3. By the slidable connection of the front door actuated member with the latch bolt 12 and the association of the coil springs therewith, it will be obvious that they are not only individually movable relative to each other, but are also movable in unison.

Secured to the inner face of the front door C by screws or the like 18 is a right angle strike plate 19 having its inwardly directed portion 20 arranged to engage with the beveled face of the cam block 8 when closing the front door for urg-

ing and holding the latch bolt 12 toward and within an open type keeper 21 that is secured to the inner face of the rear door by screws or the like 22.

The latch bolt 12 is likewise provided with a beveled face for cooperation with the beveled free end 23 of the keeper 21, in order to allow the rear door to be closed and locked when the front door is closed, as from Figure 1, it will be noted that when the front door is closed, the latch bolt 12 extends through the casing in the path of the keeper carried by the rear door, and is held accordingly by the spring 14. However, when the front door is open, the cam block is urged and held outwardly of the casing by the coil springs 16 and when in that position, the latch bolt 12 is held within the casing, as shown in Figure 3. The cam block is held in its latter position, for disposal in the path of the front door, which when closed, the strike plate 19 will engage the beveled face of the cam block and move the same within the casing to allow the latch bolt 12 to move to its operative position in the path of or within the keeper 21, it depending of course whether the rear door is open or closed, but in any event when both doors are closed, the latch bolt 12 holds the rear door securely locked, and the rear door cannot be opened until the front door is open to release the latch bolt from its keeper.

The concealed form of my lock as shown in Figure 6 is similar in many respects to the other form, and in fact the only material difference is in the structure of the strike plate and keeper. However, the casing 24 is preferably provided with beveled ends to follow the shape of the sides of the center post D in that the casing 24 is disposed and secured within the post which is mortised for that purpose, as shown. All of the parts within the casing 24 are identical to those of the form of Figures 1 to 5 inclusive, consequently description thereof is unnecessary. The strike plate 25 for the cam block 8 is carried by the front door E, and in this form, is countersunk therein, as well as fixed thereto by screws, as shown. The keeper 26 is countersunk within

the rear door F and includes a recess 27 for receiving the latch bolt 12. The operation of the form of Figure 6 is likewise identical to that of the other form.

5 Due to the fact that the post D must be mortised for receiving the casing 24 of the form of Figure 6 and the strike plate 25 and keeper 26 are countersunk within the doors, it is preferred that it be installed on new vehicles before leaving the factory, while the other form is preferred for cars now in general use, in that it can be installed thereon in an easy and expeditious manner, and merely by the use of a screw driver.

10 It is thought from the foregoing description that the advantages and novel features of the invention will be readily apparent.

15 It is to be understood that changes may be made in the construction and in the combination and arrangement of the several parts, provided that such changes fall within the scope of the appended claim.

20 What I claim is:

25 A rear door lock for a vehicle including a front door provided with striking means, a rear door provided with a keeper and a center post between said doors, said lock comprising a casing secured to the center post, a pair of aligned lugs secured within the casing, latching means mounted in the casing and including a bolt for disposal 30 in the keeper for locking the rear door in closed position, a T-shaped stem formed on the bolt, cam means slidably mounted in and through the casing and including a block having a beveled face for disposal in the path of the striking means, a 35 pair of parallel T-shaped stems formed on the block and having the head of the stem of the bolt slidably between the same for interconnecting the stems of the block and bolt for normally holding the bolt out of latched position, a spring 40 between the block and the head of the bolt stem for urging the bolt to latched position, and springs between the lugs and the block for urging the latter in the path of the striking means to be moved thereby upon closing the front door 45 to allow the bolt to move to latched position.

JOHN A. LAMB.
